UNITED STATES PATENT OFFICE.

VERNON ROYLE, OF PATERSON, NEW JERSEY.

CYLINDER-ROUTING MACHINE.

SPECIFICATION forming part of Letters Patent No. 695,119, dated March 11, 1902.

Application filed November 13, 1899. Serial No. 736,834. (No model.)

To all whom it may concern:

Be it known that I, VERNON ROYLE, a citizen of the United States, and a resident of Paterson, in the county of Passaic and State 5 of New Jersey, have invented a new and useful Cylinder-Routing Machine, of which the following is a specification.

My invention relates to a cylinder-routing machine in which the cylinder to be operated upon and the cutting-tool are arranged the one to move bodily toward and away from the other and the cutting-tool to follow a line corresponding to an element of surface of the cylinder and a line transverse to the element 15 of surface, the several movements of the tool and the cylinder to be routed being within convenient control of the operator.

In the accompanying drawings, Figure 1 is a view of the machine in front elevation, the 20 position of the cylinder to be routed being indicated by a broken line. Fig. 2 is an end view of the same. Fig. 3 is a top plan view. Fig. 4 is a view in detail showing the means for chucking the cylinder. Fig. 5 is an enlarged view in detail of the means for adjusting the cylinder-operating mechanism in different positions relative to the operator. Fig. 25 6 is a vertical section of the same along the line 6 6 of Fig. 5. Fig. 7 is a top plan view 30 of the parts represented in Fig. 6. Fig. 8 is an enlarged view in detail, showing the drum for applying tension to the wire which transmits a rotary motion to the cylinder. Fig. 9 is a top plan view of the drum, and Fig. 10 is 35 a plan view of the lower section of the drum.

The machine illustrated in the accompanying drawings to show a practical embodiment of my invention provides for mounting cylinders of varying diameters and varying lengths, 40 so that their upper element of surface will occupy a predetermined position in space and so arranging the cutting-tool that it may be moved bodily toward and away from the cylinder at any point along its upper element of 45 surface, while the cylinder itself may be rotated back and forth at will beneath the cutter to permit the latter to operate upon the cylinder at any point of the periphery desired.

The column which forms the main support 50 for the operating parts is denoted by A and is extended laterally at its base a to form a stable support. The cylinder to be routed is

supported, primarily, from the base of the column A, and the cutting-tool, together with a slide and way for conducting the tool along 55 the upper element of surface of the cylinder, are pivoted, primarily, to the top a' of the column A, which in the present instance is given a rearward and upward slant from the body of the column, as clearly indicated in 60 Fig. 2.

The support, vertical adjustment, and rotary adjustment of the cylinder are provided for as follows: A pair of hollow pedestals B B' are fixed to the front of the base a of the column and on these pedestals worm-wheels C C' are mounted, having fixed to rotate therewith nuts b b'. The worm-wheels C C' are rotated by worms (not shown) on a shaft c, mounted in suitable bearings fixed to the pedestals B B', 70 the said shaft being rotated by means of a crank-wheel c'. A horizontal way D is located above the pedestals B B' and from it depend screws d d', which screws engage the nuts b b' and pass through the worm-wheels C C' into 75 the hollow pedestals B B'. It therefore follows that when the shaft c is rotated by the crank-wheel c' the way D and the parts carried thereby will be elevated or lowered by the action of the nuts b b' on the screws d d'. The 80 way D is guided and held steadily by means of rearwardly-extending arms d², which have a sliding connection at their ends with depending rods a², fixed to the column A. On the way D are mounted a head-block E and a 85 tail-block E'. The blocks E E' have a dovetailed engagement with the way D and are split, as shown at e, Fig. 2, and provided with a through-bolt e' for the purpose of locking them to the way D in any desired adjustment. 90 The blocks E E' are connected by a shaft e², rotatably mounted therein, and provided with chucks e³ e⁴ for holding the cylinder in position on the shaft.

The arrangement for holding cylinders of 95 varying lengths on the shaft e² is as follows: The tail-chuck e⁴ is made bodily adjustable along the shaft e² at frequent intervals—in the present instance by means of a pin e⁵, which extends through the base of the chuck 100 and through one of the openings e⁶ in the shaft. This serves to locate the two chucks a distance apart corresponding to the length of the cylinder to a degree equal to or less

than the distance between two consecutive holes e^6 in the shaft, and the two chucks are then drawn into snug engagement with the cylinder by means of a draw-bolt F , provided 5 with an operating-wheel f , extending through a sleeve f' , (see Fig. 4,) in which the head-chuck e^3 is held, and into screw-threaded engagement with a socket e^7 in the end of the shaft e^2 . By turning the draw-bolt F the 10 shaft e^2 , with the tail-chuck e^4 , fixed thereon, will be moved longitudinally, carrying the chuck e^4 toward or away from the chuck e^3 to clamp or release the cylinder, as may be required. The cylinder, no matter what its 15 diameter and length, may thus be clamped in position between the head and tail blocks E E' , and by raising and lowering the way D the upper element of surface of the cylinder may be brought into a predetermined position in 20 space ready for operation. When so adjusted, the cylinder may be rotated, together with the shaft e^2 , as follows: The sleeve f' , which carries the draw-bolt F and chuck e^3 , is mounted in suitable bearings in the head-block E , 25 and the wheel G , for operating the shaft e^2 and the cylinder thereon, is fixed to the sleeve f' , as clearly shown in Fig. 4. A wire g , through which power is transmitted to the wheel G , after passing one or more times 30 around the wheel G extends downwardly upon opposite sides of the head-block E , thence under guide-pulleys $g' g^2$, the one at the front and the other at the rear of the way D , the one part extending along the rear of the way 35 D to the upper section H of the tension-drum, to which it is secured after passing one or more times around the drum-section, and the other part extending along the front of the way D to and one or more times around the 40 operating-wheel I , and thence to the lower drum-section H' , to which, after passing one or more times around its periphery, it is secured.

The wire g is held constantly under the desired tension by the drum composed of the 45 sections H H' , to the former of which, as hereinabove stated, the part of the wire to the rear of the way is attached and to the latter of which the part of the wire at the front of 50 the way is attached. These two sections H H' of the drum are mounted to rotate horizontally relatively to each other, the lower section H' being in the present instance fastened to an upright shaft h and having the 55 upper section H loosely mounted on the hub of the lower section H' . The lower section H' has fixed to its upper side a ring h' , having gear-teeth on its periphery, and these teeth on the ring h' are engaged by a pinion h^2 , 60 fixed on a short rock-shaft h^3 , extending upwardly through a bearing in the upper drum-section H and having fixed to its upper end a lever-arm h^4 , the free end of which is attached by a spring h^5 with a stud h^6 , set in 65 the top of the section H . It thus follows that the sections H and H' of the drum are connected by means of the pinion h^2 and gearing

h' , so that, assuming the upper section H to be for the moment stationary, the tension of the spring h^5 , tending to draw the end of the 70 lever h^4 toward the stud h^6 , will tend to rotate the lower section H' of the drum in the direction to wind the wire g at the front of the way on the drum, and hence hold it taut. On the other hand, assuming the lower section H' to 75 be stationary, the spring h^5 will tend to rotate the pinion h^2 , and hence to cause it and the drum-section H , which carries it, to travel relatively to the lower section in a direction to wind the part of the wire at the rear of the 80 way on the said upper section H , and hence hold it taut. In practice the one or the other of the sections H H' will give way as the tension becomes too great on it until it is balanced by the tension upon the companion 85 section, so that the two parts will be at all times under equal tension, which is to be primarily determined by the strength of the spring h^5 .

I further provide for the slight raising and 90 lowering of the drum H H' as it winds and unwinds the wire to prevent the layers of wire from overlapping one another. This is accomplished as follows: The shaft h has in 95 its upper end an interiorly-screw-threaded socket h^7 , which engages a fixed screw h^8 , set in the top of the way D and fixed against a rotary movement. The pitch of the screw h^8 is such that as the drum-sections H H' rotate and carry with them the shaft h it will, by 100 its screw-threaded engagement with the screw h^8 , gradually raise and lower to accommodate the position of the wire thereon.

The wire-operating wheel I has fixed to its front a ring i , provided on its periphery with 105 gear-teeth which engage a pinion i' on a shaft i^2 , which extends forwardly and carries on its front end a star-wheel i^3 . It is desirable that the star-wheel i^3 , some one of the arms of which are grasped by the operator to operate 110 the wire g , and hence rotate the cylinder, should be within convenient reach of the operator at all points throughout the length of the cylinder wherever the cutter may be at work, and to this end I have provided means 115 for raising and lowering the star-wheel and also for moving it bodily along the way D without disturbing the engagement of the wheel I with the wire. In the present instance the star-wheel is provided with four 120 arms; but it may be provided with a greater or lesser number of arms, as may be found desirable. It and its shaft carrying the pinion i' are mounted in a bracket i^4 , fixed to or formed integral with a housing i^5 , arranged 125 to protect the gearing and provided with a hub i^6 , which forms a bearing for the wire-operating wheel I and which in turn is mounted on a hollow axle i^7 , fixed in the depending front portion k of a slide K , fitted to the way 130 D . The axle i^7 is conveniently screwed into the depending front k of the slide and carries a head i^8 at its front end, which serves to hold the hub i^6 tightly against the front k of the

slide in whatever position the star-wheel may be adjusted in its rotary adjustment around the wheel I. For example, if the star-wheel, when the pinion i' is at the top of the toothed ring i , be too high the axle i^7 may be loosened by applying a wrench to its head i^8 , and the housing i^5 , together with its bracket carrying the star-wheel and its pinion i' , may be rocked on the axle i^7 either to the left or right, the 5 pinion i' working idly in the teeth in the ring i until the star-wheel has reached the position desired, and in that position it may be firmly locked by screwing the axle i^7 into the front k of the slide, so as to cramp the hub 10 i^6 firmly between the head i^8 of the axle and the front face of the part k . In addition to this bodily upward and downward adjustment of the star-wheel it and the parts connected with the slide K may be bodily adjusted 15 along the way D and locked in position by means of one or more vertically-movable locking-pins—in the present instance two, denoted by L and L'—arranged to move vertically in sockets formed in the depending portion 20 of the slide, as shown in Figs. 5, 6, and 7, and having their upper ends wedge-shaped, so that when they are forced upwardly they will wedge between the front of the way D and the rear of the depending portion k of the 25 slide, and hence lock the slide in position, and when allowed to drop will release the slide K and permit it and the parts carried thereby to be moved along the way D. Power is applied to and removed from the pins LL' by 30 means of an angle-dog mounted on a pin l , held between a pair of lugs $k' k^2$ on the depending portion k of the slide. The angle-dog is provided with an upright arm l' and with a pair of short forwardly-extending arms, (denoted by 35 $l^2 l^3$), the position of which are shown in Fig. 6, and one of which, l^3 , is shown in full lines in Fig. 5. The arms l^3 extend under the ends of the pins L L' in position to drive the pins upwardly or allow them to drop as the dog is 40 rocked on its support and the upright arm l' of the dog is in position to be engaged by a longitudinally-sliding pin l^4 , resting in the bore of the hollow axle i^7 and adapted to be driven into engagement with the arm l' of the 45 dog or released therefrom by a set-screw l^5 , which extends through the head of the axle and has a screw-threaded engagement with the interior of the axle. From this it follows that when it is desired to move the star-wheel 50 bodily along the way D to suit the position of the cutter for the time being the screw l^5 may be turned to release the pin l^4 from the angle-dog, which in turn will release the locking-pins L L' and permit the slide K to be moved 55 along the way D at pleasure, the wheel I accommodating itself to its new position by idly rotating under the friction of the wire around it. When the slide K has reached the position desired, it may be locked in a 60 moment's time by simply turning the screw l^5 into engagement with the pin l^4 , which by its engagement with the angle-dog will force 65 the locking-pins L L' and cramp the slide K securely in its place, so that when the wheel l is turned by means of the star-wheel motion 70 will be communicated through the wire to the shaft which carries the cylinder and it will be rocked the one way or the other according as the star-wheel is turned in one way or the other to bring the cylinder in the desired position with relation to the cutter. 75

The means for moving the cutter toward and away from the cylinder and along the upper element of surface of the cylinder while it is being driven at a high rate of 80 speed are as follows: A horizontal way M is supported on a pair of forwardly-extending arms $m m'$, which arms are pivotally secured to the top a' of the column A. In the present instance the top a' of the column is composed 85 of a pair of upwardly and rearwardly extending arms provided at their upper end with bearings for a rock-shaft m^2 , to which the arms $m m'$ are fixed, so as to rock together with the shaft m^2 in the bearings in the top 90 of the column. The way M extends horizontally along in proximity to the position which the top of the cylinder to be operated upon is to occupy—viz., parallel with an element of surface on the cylinder—and supports a 95 carriage N, which carries the cutter, and also means for driving the carriage back and forth along the way M. The carriage N is secured to the way M by means of yielding gibs n' , (see Fig. 2,) which serve to automatically take up wear. The yielding feature may be obtained by inserting a spring-washer n^2 beneath the nut n^3 , which holds the gib in place. 100

The mechanism for driving the carriage N 105 along the way M is quite similar in its general character to that already described for rotating the cylinder. It consists of a star-wheel O, in the present instance provided with six arms or handles and carrying a pinion o, (see Fig. 2,) in mesh with a gear-wheel o' , fixed to rotate with a wire-receiving drum o^2 , the drum, the gearing, and the star-wheel being all supported in a suitable manner on the top of the carriage N, and the shaft supporting the star-wheel and its pinion o being mounted in suitable bearings in a housing o^3 , arranged to be adjusted around the gear-wheel on the drum o^2 to bring the star-wheel nearer to or farther away from the operator 110 115 in a manner quite similar to that hereinbefore described for bringing the star-wheel i^3 into a higher or lower adjustment. The wire which engages the drum o^2 is denoted by P and is fixed at one end to a post p on the way M and at its opposite end is attached to an arm p' , fulcrumed on an adjustable pin p^2 and having its free end connected by a spring p^3 with a fixed support p^4 . The wire is connected with the arm p' near its fulcrum, so 120 125 130 that a slight spring p^3 serves to give it the desired tension, and the arm p' may be bodily adjusted toward and away from the post p , to which the opposite end of the wire is secured,

by means of the adjusting-pin p^2 , to which the arm p' is fulcrumed and which has a screw-threaded engagement with its support p^5 . In the present instance the drum o^2 , attached to the carriage, is carried bodily along the way M with the carriage as it is rotated, taking up and paying out the wire, which has a frictional engagement with it, and this motion will carry the cutter bodily along parallel with the way M .

The cutter, which may be of any well-known or approved form, is denoted by Q and may be fixed to its spindle in any well-known or approved manner, the spindle itself being mounted in a support q , having a vertical adjustment on the face of a forward projection n on the carriage N . In the present instance the cutter-spindle support has a dovetailed engagement with the front of the part n , so that cutters of varying lengths may be employed as occasion may require.

To further accommodate the cutter-support q to the rising-and-falling movement which is imparted to it as the carriage and its way are raised and lowered, I provide a jointed and longitudinally-extensible rod q' , which extends between the cutter-support q and the spindle q^2 , on which the intermediate drive-pulley R is fixed. A belt r leads from the intermediate drive-pulley R to a pulley R' on the cutter-spindle, and a belt r' leads from a drive-pulley R^2 on the drive-shaft to a pulley R^3 on the spindle q^2 , which carries the intermediate pulley R . The spindle q^2 is supported in the end of an arm s , projecting from a bracket S at the top of the column A , and the spindle q^3 , which the drive-pulley R^2 is mounted on, is supported in the bracket S and is provided with fast and loose pulleys s^1 s^2 , which are actuated by means of a belt s^3 , leading to a source of power. (Not shown.) A belt-shifter of any well-known or approved form operated by a lever s^4 serves to start and stop the action of the cutter at pleasure. It will thus be seen that the cutter-support q , while its position is determined by the carriage N along a predetermined line, which in the present instance is parallel with an element of surface of the cylinder, is connected with its driving mechanism by a jointed arm, which at the spindle q^2 as its joint permits a folding and unfolding of the arm in a horizontal direction, while the jointed rod q' permits the slight rise and fall of the cutter-support sufficient to bring the tool into and out of engagement with the cylinder as the carriage and its way are raised and lowered. The connecting-rod q' is conveniently made adjustable in length by providing one section of it with a screw-thread q^4 , which engages a screw-threaded socket q^5 in the adjacent part.

The way M and the parts superimposed thereon are raised and lowered by means of a pair of rods T T' , which extend from the free ends of the arms m m' downwardly and connect with a foot-treadle (denoted as a

whole by t) and which is supported by the pedestals B B' and which may be of any well-known or approved form. The downward movement of the arms m m' and the parts carried thereby is determined by means of a pair of adjusting-screws, (indicated in dotted lines in Fig. 3 and one of them shown in full lines in Fig. 2, denoted, respectively, by u u' .) By this means the depth of cut of the tool may be accurately determined, and the operator has only to pay attention to the lifting of the tool out of engagement with the work, so far as the upward and downward movements of the cutter are concerned.

The operation of the machine as a whole may be briefly stated as follows: The cylinder having been placed in position so as to bring its upper surface in proper relation to the cutter and the cutter having been set in motion, the operator, with one hand on the star-wheel i^3 , another on the star-wheel O , and his foot on the treadle t , controls the movement of the cylinder to bring the cutter into engagement with its surface at the proper point laterally of its length, while with the star-wheel O he moves the carriage, and hence the cutter, longitudinally along the cylinder to bring the cutter into engagement with the cylinder at the proper position lengthwise of the cylinder, and with his foot lifts the cutter out of and allows it to drop into action at pleasure. The operator thus has under his perfect control by the several adjustments within his convenient reach means for promptly and accurately bringing the cutting-tool into engagement with the cylinder at any point he pleases throughout the surface of the cylinder, and in addition to this he may operate upon cylinders of varying diameters and lengths as occasion may require.

It is obvious that changes might be resorted to in the form and arrangement of the parts without departing from the spirit and scope of my invention. Hence I do not wish to limit myself strictly to the structure hereinafter shown and described; but

What I claim is—

1. A routing-machine comprising a column, means for supporting the cylinder to be routed from the base of the column, a cutter, a carriage for supporting the cutter, a way located parallel with an element of surface on the cylinder to be routed, the carriage being engaged with and guided by the way and the said way being pivoted at the upper portion of the column to swing toward and away from the cylinder to be routed, means under the control of the operator for moving the carriage along the way during the operation of the cutter and means under the control of the operator for swinging the said way, at pleasure, during the operation of the cutter, substantially as set forth.

2. In combination, a suitable supporting-column, a way supported from the base of the column, means for vertically adjusting the way, head and tail blocks mounted on the

way, means for supporting a cylinder on said blocks, means for rotating the cylinder in either of two opposite directions, at pleasure, a cutter and means for moving the cutter toward and away from the cylinder-support, substantially as set forth.

3. In combination, a suitable supporting-column, a way supported from the base of the column, means for vertically adjusting the way, head and tail blocks mounted on the way, a cylinder-supporting shaft mounted in said blocks, means for securing the cylinder to the shaft, means for rotating the shaft in either of two opposite directions, at pleasure, a cutter and means for moving the cutter toward and away from the cylinder-support, substantially as set forth.

4. In combination, a suitable supporting-column, a way supported on the column, means for vertically adjusting the way, head and tail blocks mounted on the way, a cylinder-supporting shaft mounted in the blocks, a movable chuck carried by the shaft for accommodating cylinders of different lengths, means for rotating the shaft in either of two opposite directions, at pleasure, a cutter and means for moving the cutter toward and away from the cylinder-supporting shaft, substantially as set forth.

30 5. In combination, a suitable supporting-column, a way supported on the column, head and tail blocks mounted on the way, a cylinder-supporting shaft mounted on the blocks, a chuck secured to the shaft, means for adjusting the shaft longitudinally, means for rotating the shaft in either of two opposite directions and a cutter arranged to engage a cylinder mounted on the shaft, substantially as set forth.

40 6. In combination, a cylinder-supporting shaft, a pair of chucks, one secured to the shaft and another secured to a part independent of the shaft, means for adjusting the shaft with the chuck thereon relative to the part carrying the other chuck, means for adjusting shaft and chucks bodily along a predetermined path and a cutter arranged to engage the cylinder on the shaft, substantially as set forth.

50 7. In combination a way, head and tail blocks mounted on the way, a cylinder-supporting shaft mounted in the blocks, a pulley fixed to rotate with the shaft, a drive-wire extending around the pulley and along the way, a drive-pulley mounted on the way and engaged with the wire, means for rotating the said pulley, at pleasure, to rock the cylinder-supporting shaft and a cutter arranged to engage the cylinder supported on the shaft, substantially as set forth.

8. In combination a cylinder-supporting shaft, a wire for driving the shaft, a way, a drive-wheel engaged with the wire and supported on the way, means for operating the drive-pulley in either of two opposite directions, at pleasure, and means for adjusting the drive-pulley and its driving mechanism

bodily along the way, a cutter arranged to engage the cylinder supported on the shaft, substantially as set forth.

9. The combination with the wire belt arranged to rock the cylinder to be routed, of a drive-wheel engaged with the wire for operating it, a lever for operating the said drive-wheel and means for adjusting the lever bodily along the periphery of the drive-wheel, substantially as set forth.

10. The combination with a wire belt for operating the cylinder to be routed, of a drive-wheel engaged with the belt, a lever for operating the drive-wheel, a support for the said drive-wheel and lever, means for adjusting the drive-wheel and lever bodily along the support and means for adjusting the lever bodily along the periphery of the drive-wheel, substantially as set forth.

11. The combination with the wire belt for operating the cylinder to be routed, of a tension-drum engaged with the wire, the said drum comprising two sections, one engaged with one end of the wire and the other with the opposite end of the wire, gear connecting the two sections and a spring-actuated lever for operating the gear, substantially as set forth.

12. The tension-drum for holding the wire belt under the desired tension comprising two sections, one carrying a gear-wheel and the other a pinion free to rotate relatively to its support, the said pinion having connected therewith an operating-arm and a spring, one end of which is connected to the operating-arm and the other end to the section which carries the pinion with which the operating-arm is connected, substantially as set forth.

13. The combination with the belt-wheel for operating the cylinder to be routed, means for moving the wheel bodily along the said cylinder and the wire belt for operating the wheel, of a tension-drum for holding the wire under the desired tension, a spindle fixed to rotate with the drum and a screw having a threaded engagement with the spindle for raising and lowering the drum as the wire is unwound from and wound on the drum, substantially as set forth.

14. The combination with a main support and means for supporting a cylinder thereon, of a cutter, a carriage for supporting the cutter, a way located parallel with an element of surface on the cylinder to be operated upon, the carriage being engaged with and guided by the way and the said way being pivoted to swing toward and away from the cylinder to be operated upon, means under the control of the operator for moving the carriage along the way during the operation of the cutter, and means under the control of the operator for swinging the way, at pleasure, during the operation of the cutter, substantially as set forth.

15. The combination with the pivoted way and the cutter-supporting carriage mounted on the way, of a wire extending along the way,

a drive-wheel carried by the carriage and engaged with the wire and a lever for rotating the drive-wheel to move the carriage along the way, substantially as set forth.

- 5 16. The combination with the cutter-carriage and the way along which it is arranged to travel, of a wire stretched along the said way, a spring-actuated arm connected with the wire at one end for imparting tension
10 thereto, a carriage-operating wheel engaged with the wire and supported by the carriage,

and a lever also carried by the carriage and arranged to rotate the wheel to move the carriage along the way, substantially as set forth.

In testimony that I claim the foregoing as 15 my invention I have signed my name, in presence of two witnesses, this 18th day of October, 1899.

VERNON ROYLE.
